UNITED STATES PATENT OFFICE.

LEE J. BLACK, OF BEAUMONT, TEXAS.

CROWN BLOCK FOR DERRICKS.

Application filed May 14, 1927. Serial No. 191,455.

This invention relates to crown blocks for derricks and more particularly to the crown blocks of the derricks of oil well drilling apparatus.

An important object of the invention is to produce a device of this character which will permit the travelling block of the derrick to be moved much closer to the crown block than is possible with the ordinary construction, due to the fact that the various sheaves in the ordinary construction are arranged upon different shafts and accordingly the cable runs from these sheaves are so widely separated that they bind upon the block after it reaches a predetermined height.

A further object of the invention is to provide a construction such that the ordinary cat and hand line sheave provided may be conveniently mounted upon a portion of the sheave mounting for the main crown block sheave and in such position that the line passed thereover will not in any way interfere with the operation of the travelling block.

A still further object of the invention is to provide a crown block structure so formed that it may be very readily assembled upon the top of the derrick. It is pointed out that the assembly of the crown block structure is ordinarily a difficult and dangerous operation. The top of an oil well drilling derrick is usually one hundred and twenty-five feet from the ground and the only support for elements of the crown block which are being moved upwardly for positioning at the top of the derrick are a gin pole and hand or cat line. In the ordinary construction, a relatively heavy frame structure is necessary, which substantially covers the entire top of the derrick and this structure is accordingly very difficult to install in position.

A further object of the invention is to provide a crown block structure permitting lubrication of the main sheaves from the floor of the derrick, thus eliminating the necessity of a workman climbing to the top of the derrick at intervals to perform this operation.

These and other objects I attain by the construction shown in the accompanying drawings, wherein for the purpose of illustration is shown a preferred embodiment of my invention and wherein:

Figure 1 is a vertical sectional view

through a crown block constructed in accordance with my invention;

Figure 2 is a side elevation partially in section;

Figure 3 is a fragmentary section through the supporting structure showing the means for holding the beams in spaced relation;

Figure 4 is a section on the line 4—4 of Figure 3;

Figure 5 is an enlarged detail sectional view showing the washer bars employed for securing the brackets to the side member.

In accordance with my invention, I provide a supporting frame comprising spaced side members 10, each including a pair of beams 11 (preferably I beams) affording opposed channels 12. The beams of each side member are secured to one another and maintained in spaced relation by channel iron spacers 13, the upper and lower ends of the bases 14 of which are shaped to conform to the arms of the channel 12 and are provided with lugs 15 extending between adjacent edges of these arms, so that they are maintained in spaced relation to one another. Bolts 16 extend through the webs 17 of the beams 11 and the arms 18 of the spacers secure the elements of each side member and afford a rigid and unitary structure.

Seated upon the upper surface of each side member is a triangular bracket 19 affording aligned vertically spaced and horizontally directed bearings 20 and 21 for the reception of the ends of shafts 22 and 23. The bases 24 of the brackets 19 are apertured for the passage of securing bolts 25 which are passed through these apertures and through the space between adjacent beams 11, provided by the lugs 15 of the spacers, and openings of washer bars 26, which abut the bottom faces of the beams 11 of the side members and are formed centrally with lugs 27 acting to maintain these beams in properly spaced relation. Upon the shaft 22 between adjacent faces of the brackets 19 are mounted a plurality of sheaves 28, spacer plates 29 surrounding the shaft between adjacent sheaves 28 and having at their upper ends apertures 30 for the passage of the shaft 23. Upon the shaft 23 intermediate adjacent spacer plates 29 and intermediate the outermost spacer plates and the brackets are arranged spacer sleeves 31. It will be observed that the spacer plates and sleeves may be tied to form a very rigid structure.

and the spacer plates, since they likewise embrace the shaft 22, will serve to rigidly support this shaft from the shaft 23 and thus reinforce the same. The shaft 23 is formed at a point spaced from one end thereof with a shoulder 32 adapted to abut the outer face of one of the bearings 21 and at its opposite end is threaded for the reception of securing nuts 33 to insure proper binding together of the brackets, spacer sleeves and plates 30. The extremity of the first named end of the shaft 23 provides a mounting for a cat line sheave 33' and is extended sufficiently that a line hanging vertically from this sheave clears the outer face of the adjacent side member 10. The shaft 22 is formed at one end with a head 34 and at its opposite end is threaded for the reception of jam nuts 35 whereby this shaft 20 may be securely held in position.

In installation of the structure so far described, and after the side members 10 have been installed in position and the brackets 19 secured thereto, the shafts 22 and 23 may have their threaded ends partially inserted through the bearings 20 and 21 and each spacer sleeve 31 and its associated sheave may be hoisted to the top of the derrick as a unit and installed in position. With the installation of the final sheave and sleeve, the shafts 22 and 23 are extended through the opposite bearings and secured in position. It will be seen that since the device may be very readily assembled in its component parts, there is no necessity for the handling of an extremely heavy load at any time during this assembly and accordingly the danger and difficulty of the assembly is materially decreased.

40 In order to provide for lubrication of the sheaves 28 without the necessity of an operator climbing to the top of the derrick, the shaft 22 is formed with a bore 36 opening through the threaded end thereof. The outer end of this bore is threaded for the reception of a plug 37 having an axial bore forming a bearing for a shaft 38. The opposite end of this shaft is journaled in an axial bore 39 formed in the opposite end 50 of the shaft 22. The shaft 38 in alignment with the sheaves 28 is formed with screw sections, the ends of which are oppositely pitched and have each mounted thereon a piston 41. These pistons either by frictional engagement with the walls of the bore or any other desired means are maintained against rotation as the shaft 38 rotates and will accordingly move toward one another. The bearings 42 are in communication with 60 the space 43 between the pistons of each screw section through ports 44 formed in the wall of the shaft and accordingly if grease is packed in the space 43 and the shaft 38 rotated, this grease will be forced by movement of the pistons toward one

another through the ports 44 and into the bearings 42. The outer end of the shaft 38 has secured thereto a small sheave 45 over which is trained a flexible element 46, the lower end of which extends to the bottom of the derrick.

It will be obvious that by operation of this flexible element, rotation of the shaft 38 may be accomplished and accordingly grease fed to the bearings 42 without the immediate attendance of an operator. It will also be obvious that when the pistons 41 of the screw sections 40 come into engagement with one another, they will lock, apprising the operator that the grease has been exhausted and the dispensing apparatus must be replenished.

It will be obvious that in a construction of this character, not only is the actual assembly of the crown block facilitated and the travel of the traveling block materially increased, but a convenient mounting is provided for the cat line sheave, which also serves as a reinforcement for the main sheave shaft and a structure is provided, the operation of which is materially facilitated. It will also be obvious that the construction hereinbefore set forth is capable of a certain range of change and modification without materially departing from the spirit of the invention and I accordingly do not limit myself to such specific structure except as hereinafter claimed.

I claim:-

1. In a crown block structure, side members, opposed brackets supported thereby and each affording a vertically aligned pair of shaft bearings, shafts having their ends engaged in said bearings, sheaves mounted upon the lower shaft and means extending downwardly from the upper shaft and engaging the lower shaft partitioning said sheaves from one another and providing a supporting connection between the upper and lower shafts.

2. In a crown block structure, side members, opposed brackets supported thereby and each affording a vertically aligned pair of shaft bearings, shafts having their ends engaged in said bearings, sheaves mounted upon the lower shaft and means extending downwardly from the upper shaft and engaging the lower shaft partitioning said sheaves from one another and providing a supporting connection between the upper and lower shafts, the upper shaft having at one end an extension providing a mounting for a further sheave.

3. In a crown block structure, side members, opposed brackets supported thereby and each affording a vertically aligned pair of shaft bearings, shafts having their ends engaged in said bearings, sheaves mounted upon the lower shaft, means extending downwardly from the upper shaft and engaging

the lower shaft partitioning said sheaves from one another and providing a supporting connection between the upper and lower shafts, said side members each including 5 parallel beams and spacers maintaining adjacent edges of the beams in spaced relation to one another, securing elements for said brackets extending through the spaces thus provided and washer bars at the lower faces 10 of said beams through which said securing elements extend.

4. In a crown block structure, side members, opposed brackets supported thereby and each affording a vertically aligned pair 15 of shaft bearings, shafts having their ends engaged in said bearings, sheaves mounted upon the lower shaft, means extending downwardly from the upper shaft and engaging the lower shaft partitioning said sheaves 20 from one another and providing a supporting connection between the upper and lower shafts, spacers upon said upper shaft intermediate said means, means upon the shaft engaging opposite faces of the brackets for 25 clamping the brackets, spacers and said means to form a rigid assembly.

5. In a crown block structure, side members, opposed brackets supported thereby and each affording a vertically aligned pair 30 of shaft bearings, shafts having their ends engaged in said bearings, sheaves mounted

upon the lower shaft, means extending downwardly from the upper shaft and engaging the lower shaft partitioning said sheaves from one another and providing a supporting connection between the upper and lower shafts, spacers upon said upper shaft intermediate said means, means upon the shaft 35 engaging opposite faces of the brackets for clamping the brackets, spacers and said 40 means to form a rigid assembly, the upper shaft having at one end an extension and a sheave rotatably mounted upon said extension and rotating in a plane lying to one side of the adjacent side member. 45

6. In a crown block structure, side members, opposed brackets supported thereby, a pair of vertically aligned parallel shafts having their ends supported in the brackets, a plurality of sheaves mounted upon the 50 lower shaft intermediate the brackets, parallel plates for said sheaves surrounding the lower shaft and supported from the upper shaft, spacers surrounding the upper shaft 55 between the partition plates, the upper shaft embodying means for clamping said brackets upon said spacers and parallel plates to provide a rigid structure, said upper shaft at one end thereof outwardly of the adjacent bracket having mounted thereon a sheave. 60

In testimony whereof I affix my signature.
LEE J. BLACK.
